UNITED STATES PATENT OFFICE.

GEORGE W. GIFFORD, OF KINSLEY, KANSAS, ASSIGNOR OF ONE-HALF TO
HARRY LINN READ, OF SAME PLACE.

END-GATE.

SPECIFICATION forming part of Letters Patent No. 682,610, dated September 17, 1901.

Application filed June 8, 1901. Serial No. 63,781. (No model.)

To all whom it may concern:

Be it known that I, GEORGE W. GIFFORD, a citizen of the United States, residing at Kinsley, in the county of Edwards and State of 5 Kansas, have invented a new and useful End-Gate, of which the following is a specification.

The invention relates to improvements in end-gates.

One object of the present invention is to improve the construction of end-gates and to provide a simple, inexpensive, and efficient device capable of securely locking an end-gate in position on a wagon-body and adapted to prevent the sides of the wagon-body from 15 spreading when subjected to a heavy strain and the end-gate from jumping up and down when the wagon is traveling over rough roads.

Another object of the invention is to provide a device of this character which will prevent loss of grain or other material and which will enable an end-gate to be readily placed in and removed from a wagon-body.

The invention consists in the construction and novel combination and arrangement of 25 parts hereinafter fully described, illustrated in the accompanying drawings, and pointed out in the claims hereto appended.

In the drawings, Figure 1 is a perspective view of an end-gate constructed in accordance with this invention. Fig. 2 is a horizontal sectional view of the same. Fig. 3 is 30 a detail sectional view illustrating the construction of the locking mechanism. Fig. 4 is a detail view of one of the links. Fig. 5 is 35 a detail view illustrating the construction of the ends of the sliding bars. Fig. 6 is a detail view of a portion of one of the catches. Fig. 7 is a detail view of the bracket. Fig. 8 is a perspective view illustrating a modification 40 of the invention. Fig. 9 is a horizontal sectional view of the same, the sliding bars being in engagement with the catches. Fig. 10 is a similar view, the sliding bars being extended. Fig. 11 is a detail view of the cam. Fig. 12 is a similar view of one of the catches. 45

Like numerals of reference designate corresponding parts in all the figures of the drawings.

1 and 2 designate approximately U-shaped 50 sliding bars mounted in suitable guides 3 of an end-gate and having heads 4 at the termin-

nals of their upper and lower sides for engaging the sides 5 of a wagon-body, as clearly illustrated in Fig. 1 of the accompanying drawings. The guides, which may be constructed in any suitable manner, may be advantageously constructed of metal bars secured to the outer face of the end-gate, as clearly shown in Fig. 2, and bent outward between their ends to receive the upper and lower sides of the sliding bars. The sides 5 of the wagon-body are provided with upper and lower slots 6 for the reception of the ends of the sliding bars, and they are provided also with upper and lower catches consisting of 65 hooks 7, arranged in pairs to receive the ends of the sliding bars and provided with suitable shoulders for engaging the heads 4. The sliding bars are adapted to be distended to enable them to be placed in and removed from 70 the spaces between the hooks, and they are adapted to be drawn inward by the means hereinafter described to engage the heads 4 with the shoulders. The heads 4 consist of laterally-projecting arms or lugs which form 75 approximately T-shaped ends, as clearly illustrated in Figs. 1 and 5 of the drawings. The catches are formed integral with vertical bars 8, and the latter are supported by curved braces 9 and are provided with reduced lower 80 ends 10, which are threaded for the reception of nuts 11. The lower threaded ends of the bars 8 extend through the bottom 12 of the wagon-body and through a bottom cleat 13, and the said bars and the substantially semi-circular braces 9 are perforated for the reception 85 of screws or other suitable fastening devices for securing them to the sides of the wagon-body. By this construction the sides of the wagon-body are reinforced at the rear 90 ends, where they are connected with the end-gate 14, and the latter is securely interlocked with the said sides, so that there is no liability of the end-gate jumping up or down or the sides spreading, and there will be no loss of 95 grain or other material from such causes.

The U-shaped sliding bars are provided at their bends or inner portions with ears 15 and 16, arranged in pairs and perforated for the reception of pivots 17 and 18 for connecting them to the outer ends of links 19 and 20. The inner ends of the links 19 and 20 are se-

cured by pivots 21 and 22 in a bifurcation 23 of an operating-lever 24, which is fulcrumed between the said pivots 21 and 22. The operating-lever is perforated for the reception 5 of a pivot and is arranged between a pair of arms 25 of a bracket 26, and it is adapted to be oscillated to reciprocate the sliding bars 1 and 2. The bracket is secured to the inner face of the end-gate and the arms extend 10 through an opening of the same; but the bracket may be mounted in any other suitable manner. The outer portion of the operating-lever is adapted to be swung to and from the end-gate, and it is provided at its 15 outer end with a handle or grip. The link 20 is provided at its outer end with an arm 27, forming a keeper, and adapted to extend through an opening 28 of the lever and to be engaged by a pivoted latch 29, whereby the 20 lever is securely locked in the position shown in Fig. 1. The link is also provided with a resilient catch 30, having a beveled head and adapted to extend through the opening 28 and engage the outer edge of the operating-lever. 25 When the operating-lever is swung inward to the position shown in Fig. 1, it is automatically engaged by the resilient catch, which is arranged parallel with the arm or keeper 27. The slot or bifurcation of the inner end of the operating-lever receives the 30 inner portions of the links when the end-gate is locked.

In Figs. 8 to 12, inclusive, is illustrated a modification of the invention, in which the 35 sliding U-shaped bars 31 are provided with inner arms or shanks 32, arranged in a groove 34 of the end-gate 35 and terminating in lugs or projections 36, which engage cam-grooves 37 of an oscillatory cam or shaft 38. The cam 40 or shaft 38 is provided at its ends with suitable journals 39, which are arranged in bearings of brackets 40, secured to the outer face of the end-gate and provided at their inner edges with recesses to receive the shanks or 45 arms of the U-shaped bars. The cam or shaft is adapted to be partially rotated, and for this purpose it is provided with an arm or handle 41, having an opening 42 adapted to receive a catch 43, mounted on the end-gate 50 and arranged below the cam, as clearly illustrated in Fig. 8. The catch consists of a resilient stem or shank secured to the end-gate and arranged horizontally and provided at its outer end with a head. When the shaft 55 or cam is partially rotated, the cam-grooves reciprocate the sliding bars, which are mounted in suitable guides 44 of the end-gate. The guides consist of cleats provided with suitable recesses or openings and secured to the 60 outer face of the end-gate, as shown.

The U-shaped bars are provided at their ends with heads 45, which engage upper and lower catches 46 of the sides of the wagon-body, which are slotted, as before explained. 65 The catches consist of hooks arranged in pairs and formed integral with plates, and the latter are provided at their inner faces with re-

cesses 47, adapted to receive bars or cleats and designed to be applied to a wagon-body after the same has been constructed. The 70 plates of the catches are adapted to straddle or fit over such cleats or bars, and they may also be readily applied to the top box of a wagon-body. When the fastening device is used on a top box, a straight sliding bar may be employed instead of a U-shaped bar, and only 75 one catch for each side will be necessary.

It will be seen that the end-gate is simple and comparatively inexpensive in construction, that it is adapted to be readily placed 80 in and removed from a wagon-body, and that it securely holds the sides and is effectually held against vertical movement.

What I claim is—

1. In a device of the class described, the combination with a wagon-body, of catches fixed to the sides of the wagon-body and consisting of rigid hooks arranged in pairs and spaced apart, sliding bars extending between the hooks and provided at their outer ends with 90 heads for engaging the same, and means for moving the bars inward and outward to engage them with and disengage them from the catches, substantially as described. 85

2. In a device of the class described, the combination with a wagon-body, and an end-gate, of the U-shaped horizontally-movable bars slidably mounted on the end-gate and capable of reciprocation to engage them with and disengage them from the wagon-body, 100 and means for reciprocating the bars and for locking them in engagement with the body, substantially as described. 95

3. In a device of the class described, the combination with a wagon-body, and an end-gate, of the bars provided with curved braces and having upper and lower catches consisting of hooks arranged in pairs, the approximately U-shaped sliding bars provided at 105 their ends with heads engaging the catches, 110 and means for reciprocating the sliding bars and for locking them in engagement with the catches, substantially as described. 115

4. In a device of the class described, the combination of a wagon-body provided at opposite sides with slots, an end-gate, catches consisting of hooks arranged at opposite sides of the slots, sliding bars mounted on the end-gate and having heads for engaging the hooks, and means for reciprocating the locking-bar and for holding the heads in engagement with the hooks, substantially as described. 120

5. In a device of the class described, the combination with a wagon-body, and an end-gate, of sliding bars for engaging the wagon-body, links connected with the sliding bars, one of the links being provided with a projecting arm, a lever fulcrumed between its ends on the end-gate and connected with the 125 inner ends of said links and adapted to swing to and from the said arms, and means for securing it to the arms, substantially as described. 130

6. In a device of the class described, the combination with a wagon-body, and an end-gate, of sliding bars mounted on the end-gate and engaging the wagon-body, a lever fulcrummed between its ends, links pivoted to the lever at opposite sides of the fulcrum-point and connected with the sliding bars, one of the links being provided with an arm, a locking device for securing the lever to the arm,

and a catch mounted on the arm and engaging the lever, substantially as described.

In testimony that I claim the foregoing as my own I have hereto affixed my signature in the presence of two witnesses.

GEORGE W. GIFFORD.
